CONVERTIBLE SEAT OR SIMILAR ARTICLE OF FURNITURE

Frank W. Petersilie, Boone, N.C., assignor to Investments and Innovative Concepts, Inc., Boone, N.C.

Filed Aug. 29, 1974, Ser. No. 501,625

Term of patent 14 years

Int. Cl. D6—01

U.S. CL. D6—37

FIG. 1 is a front perspective view of a convertible seat showing my new design;

FIG. 2 is a top plan view of the convertible seat of FIG. 1;

FIG. 3 is a rear perspective view of the convertible seat of FIG. 1;

FIG. 4 is a front perspective view of the convertible seat of FIG. 1 being folded over for converting into a bed or similar article;

FIG. 5 is a perspective view of the convertible seat converted into a bed or similar article; and

FIG. 6 is a top plan view of the convertible seat converted into a bed or similar article of FIG. 5.

I claim:

The ornamental design for convertible seat or similar article of furniture, substantially as shown.
